UNITED STATES PATENT OFFICE.

CARL A. LOHMAN, OF SEATTLE, WASHINGTON.

LUMBER-BUNDLING FRAME.

1,271,046.

Specification of Letters Patent.

Patented July 2, 1918.

Application filed November 6, 1916. Serial No. 129,686.

To all whom it may concern:

Be it known that I, CARL A. LOHMAN, a citizen of the United States, and resident of the city of Seattle, county of King, and 5 State of Washington, have invented certain new and useful Improvements in Lumber-Bundling Frames, of which the following is a specification.

My invention relates to frames or like devices which are designed to bind and hold 10 a mass of lumber into a compact bundle for convenience in handling the same and more particularly for use in binding together lumber preparatory to drying the same in 15 a kiln.

The object of my invention is to provide a bundle binding mechanism which may be conveniently used and which will securely hold the bundle of lumber together while it 20 is being dried in the kiln, and also to provide a mechanism of this sort which will automatically tighten up upon the bundle as the material shrinks in drying.

The features of novelty of my invention 25 will be herein described and then particularly pointed out in the claims.

In the accompanying drawings I have shown my invention in the form of construction which is now most preferred by me.

30 Figure 1 is an end view of a bundle showing my device applied thereto, the same being in the position in which it is placed while in the kiln.

Fig. 2 is an edge view of one of the 35 binding frames.

Fig. 3 is a section taken lengthwise the frame 1 of Fig. 1, showing the manner of detachably securing the bar 3 thereto.

Fig. 4 is a face view of the same corner 40 of the frame.

Fig. 5 is a cross section through the bars of the main and of the tightening frame.

Fig. 6 is a side view of a bundle in the 45 position it is in when the piling has been completed and before placing in the kiln.

In the plan of operation under which my device is intended to be used, the lumber 50 is piled to form large bundles, which bundles are maintained intact while the lumber is in the kiln. The lumber is thus placed in the kiln in large quantities and taken out in similar quantities. So far as it is convenient to do so, it is desirable that the lumber for forming these bundles be sorted as to 55 length, so that all the lumber in any one

bundle be of the same length. My device is, however, not limited to use under these conditions, although these conditions are such as are preferred for best results.

In building these piles I prefer to use not 60 less than three binding frames for any one pile, unless this pile is of very short stock. I prefer that these be placed as is indicated in Fig. 6, with a frame close to each end of the bundle and one or more intermediate the 65 ends, the number depending upon the length of the stock.

The binding frames consist of what may be called a main or bundle-encircling frame and a binding frame. The bundle-encircling frame consists of two parts which are detachably secured together when in use. One part consists of a bar 1 and a bar 10, which are secured together by their ends in 70 right angular position, thus forming an 75 L-shaped structure. The proportions of the two sides may vary. I have herein shown them as of equal length.

The other portions of this bundle-encircling frame consists of a bar 3, which is 80 secured by one end to the end of bar 1, to form a third side of a rectangle, and a tie-rod 7, which connects the free ends of bars 3 and 10, and forms the fourth side of the 85 rectangle.

The ends of these bars 3 and 7 are secured, respectively, to bars 1 and 10, in such manner that they may be attached and detached therefrom. The manner of securing the bars 1 and 3 together, which has been herein 90 shown, consists in providing the bar 1, which is herein shown as a channel bar, with up-standing lugs 12, herein shown as composed of short sections of angle bar, which are riveted in place between the flanges of the 95 channel 1. These are provided each with a hole for the reception of a bolt 13, which bolt projects beyond the end of the bar 1 and is intended to pass through a hole in the outer flange of the bar 3. The inner flange of the 100 bar 3 is cut away for a distance equal to the width of the bar 1, thus forming a shoulder at 105 30. The bolt 13 is threaded a sufficient distance so that the bar 3 may be drawn up or adjusted until the outer flange contacts 110 with the end of the bar 1. The tie-rod 7 passes through holes in the other end of the bar 3 and the corresponding end of the bar 10. By removing the nut which secures this bar to the bar 10 and the nut upon the outer

end of the rod 13, the two bars 3 and 7 may be removed. This is done while the bundle is being formed.

The bundle binding frame consists of two bars 2 and 20, which are herein shown as composed of channels. These bars are secured in parallel relation with the bars 1 and 10 of the bundle-encircling frame, and are secured thereto in such manner that they 5 may have a limited movement in a direction diagonal to the rectangle and the bundle of lumber. This direction is across the angle between the two parts, 2 and 20. The preferred manner of doing this consists in providing one of the frames, as the binding frame 2, with diagonally positioned slots 21, and in providing the other frame, in this case the main frame, with pins or projections which enter such slots and act as 10 guides to compel movement in the direction desired. This construction is better illustrated in Fig. 5.

The bar 1 is shown as provided with a hole, through which passes a pin 40, which 15 projects from one side of a spacing block 4. This pin is preferably of non-circular outline, or of some equivalent construction by which it is held against turning. The block 4 has a like pin 41, projecting from its opposite side which passes through the slot 21. Cotter pins 42, or a like expedient, are employed to prevent separation of the bars.

The position of these slots and the guide pins 40 is such that, when one of the bars, 20 as the bar 2, is exactly opposite the companion bar 10 of the frame, the other bar 20 is off-set laterally inward with relation to its companion bar 1 of the other frame.

In placing the frames for the formation 40 of the pile of lumber, the bars 2 and 10 are placed downward, or so as to have the lumber piled thereon. This position would be that in which the right hand side of the device, as shown in Fig. 1, would be down. In 45 this position the bar 20 of the tightening frame is off-set inwardly from the bar 1 of the encircling-frame. In this position of the parts, one side and the top of the pile are open, the bars 3 and 7 of the encircling- 50 frame having been removed. For convenience in piling, supporting blocks 6 and possibly dollies 5, are preferably employed, so that after the pile has been formed it may be conveniently moved to any point desired by 55 removing the blocks 6.

In placing the bundle in the dry kiln, it is turned over into the position shown in Fig. 1. In this position the weight of the lumber is taken upon the bar 20 of the tightening 60 frame. By reason of the fact that the bars of the tightening frame are connected with the encircling-frame, through the medium of the inclined surfaces of the slots 21, the weight of the lumber causes the bar 20 to slide downward and laterally. This carries with it the

upstanding bar 2. This causes the weight of the lumber to act to bind it tightly and this action may take place to a greater degree after the bundle has been placed in the kiln, thereby automatically compensating 70 for the shrinkage of the lumber.

By the use of a device of this sort, the binding of the bundle may be very securely done and also quickly and with slight labor. The bundle is held securely while in the kiln 75 and a considerable quantity may be handled at once. For this purpose mechanism of the nature of cars, trucks, cranes, etc., may be employed.

What I claim as my invention is:

1. A bundling device for lumber comprising a bundle encircling frame, a bundle clamping frame containing two bars secured by their ends to make an angular frame adapted to engage two adjacent sides of the bundle, one of said frames having diagonal slots and the other members sliding in said slots, whereby the frames may have a limited relative movement diagonally of the frames. 85

2. A bundling frame for lumber comprising a bundle encircling frame containing two bars secured by their ends in right angular relation, and two other bars secured together in like relation, means for detachably securing said pairs of bars together to form a rectangle, said securing means providing for a limited adjustment in the size of the rectangle, a bundle clamping frame comprising two bars with their ends secured together in rectangular relation and means securing said clamping frame upon the other frame to permit diagonal relative movement between them. 95

3. A bundling frame for lumber comprising a bundle encircling frame containing two bars secured by their ends in right angular relation, and two other bars secured together in like relation, means for detachably securing said pairs of bars together to form a rectangle, said securing means providing for a limited adjustment in the size of the rectangle, a bundle clamping bar secured in parallel relation with one of the bars of said rectangular frame, and means actuated by the weight of the lumber to bind said clamping bar against the pile of lumber. 105

4. A bundling frame for lumber comprising a bundle encircling frame containing two bars secured by their ends in right angular relation, and two other bars secured together in like relation, means for detachably securing said pairs of bars together to form a rectangle, said securing means providing for a limited adjustment in the size 110 of the rectangle, a bundle clamping frame having two bars adapted to engage adjacent sides of the bundle inwardly of the inner edges of the bars of the other frame, the bars of said two frames being secured to- 115

120

125

130

gether by means permitting diagonal relative movement between the two.

5. A bundling frame for lumber comprising a bundle encircling frame having two bars fixed together by their ends in right angular relation, a bar forming a third side of the rectangle and secured by one end to an end of one of the other bars by a threaded member to permit adjustment and disengagement, and a tie rod connecting bars to

form the fourth side of the rectangle, a clamping frame composed of two bars and means securing said bars in parallel relation to the two first named bars and permitting relative movement diagonally of the 15 rectangle.

Signed at Seattle, Washington, this 30th day of October, 1916.

CARL A. LOHMAN.
